SPRINKLER

Albert J. Loepsinger, Providence, R. I., assignor to
General Fire Extinguisher Company, Providence,
R. I., a corporation of Delaware.

Application April 14, 1931, Serial No. 529,904

4 Claims. (Cl. 169—37)

This invention relates to improvements in sprinklers. More especially it has to do with a sprinkler capable of distributing its discharge over a substantially rectangular area.

5 Sprinklers now in common use distribute their discharge over a circular area. When installing a sprinkler system employing such sprinklers the latter must be so located with respect to one another that their combined discharge covers all 10 the area to be protected. This requirement, coupled with the circular area served by each 15 sprinkler results in a large overlapping of area which is not only unnecessary but is also undesirable for it leads to excessive discharge and needless water damage.

It is an object of this invention to provide a 20 sprinkler which will enable the aforesaid overlapping to be reduced to a necessary minimum and which will permit a less quantity of water to be discharged from each sprinkler albeit the 25 intensity of precipitation is no less than is now deemed suitable. Clearly if the proposed sprinkler actually discharges a smaller quantity of water it must follow that the water damage is correspondingly reduced.

The best mode in which I have contemplated applying the principles of this invention is illustrated in the accompanying drawing but it is intended that the patent shall cover by suitable 30 expression in the appended claims whatever features of patentable novelty exist in the invention disclosed.

In the drawing,

Figure 1 represents the plan view of an area to 35 be protected, with the unit area served by each improved sprinkler indicated by the heavy dotted lines, and with the corresponding area of the present day sprinklers represented by a dot-and-dash circle;

40 Figure 2 is a plan view of a sprinkler embodying the invention;

Figure 3 is an elevation of the same; and

Figure 4 is a partial elevation with the deflector shown in section as on line 4—4 of Figure 2.

45 Referring more particularly to the drawing, there is represented in Figure 1 a floor area of a building having side walls *a* and *b* and an end wall *c*. Under the present practice of installing sprinkler systems heads would be located at the 50 various points marked *d* and the area of distribution served by each such head is represented by the dot-dash circles *e*. It is to be noted that the heads are so located that no space is left un-reached by the sprinkler discharge. This results in a very considerable portion of each cir-

cular area being doubly protected, as it were, for there is of necessity a large overlapping of these circular areas. As a consequence if several 5 sprinklers are opened upon the occurrence of a fire there is bound to be an unwarranted water damage due to this overlapping alone.

The present invention enables the shape of area served by each sprinkler to be changed from the customary circular shape *e* to one which is substantially rectangular. In the particular example disclosed for purposes of illustration this area is shown as an approximate square *f*. The diagonal of the latter is substantially equal to the diameter of the circle previously covered, there being a small but ample overlapping of the 15 edges of these square areas to avoid any un-reached spaces. Since the area of each square served by a head is about seventy per cent of the area of the corresponding circle previously covered, it is possible, with seventy per cent of the 20 quantity of water heretofore discharged from each head, to sprinkle the square area with the same intensity of precipitation as before. In other words, due to the almost complete elimination of overlapping areas and the great reduction 25 in area actually served by each head the entire area can be just as effectively sprinkled as heretofore but with a saving of at least thirty per cent of the quantity of water. Consequently, when the 30 sprinklers under the improved arrangement 30 of distribution open for discharge there is necessarily a marked saving in water damage.

In Figures 2, 3, and 4 is illustrated a sprinkler *g* having a deflector *h* capable of producing the desired square area of coverage. In plan view 35 (Figure 2) the configuration of this deflector is substantially that of a square, its sides being at right angles to one another, with the tongues *h'* on each side in a straight line.

Viewed from the side (Figure 4) the center portion of the deflector is seen to be flat and to merge into downward curving side portions comprising the tongues *h'*. These side or marginal portions extend completely around the flat plate portion and each marginal flange lies in a single plane which is symmetrically disposed in angular relation to the flat plate portion. These marginal flanges impart direction to the discharge of the water received upon it, and since each such flange is in a single plane, the edge 40 of the sprinkled area corresponding to the marginal flange will be substantially a straight line edge. At each corner there is a tongue with a portion on one side thereof and another portion on the other side thereof. By a suitable 45

proportioning of the deflector, comparable with the decrease in quantity of water discharged, the area served by each head will be approximately as indicated by the heavy dotted lines *f* of Figure 1, to wit, substantially square. If the area to be covered by a sprinkler is oblong, then the deflector should be made rectangular with its longer sides proportional to the longer axis of the oblong area to be served and with the shorter side of the deflector proportional to the shorter sides of said area.

I claim:

- 15 1. A sprinkler comprising a body having a discharge opening; an arm extending from said body, constructed and arranged to support a deflector in alignment with said opening; and said deflector having a rectangular plate portion extending at right angles to the axis of flow through said opening and having marginal portions arranged at an abrupt angle to said plate portion and forming a circumscribing edge on said deflector, each marginal portion being symmetrically disposed in angular relation to said deflector and constructed and arranged to impart direction to the discharge from said opening.
- 20 2. A sprinkler having an opening for discharge therethrough and a deflector mounted opposite said opening having a rectangular flat portion arranged at right angles to the axis of flow through said opening and having marginal portions circumscribing the edge of the rectangular portion, with each marginal portion being sym-

metrically disposed in angular relation to the plate portion and constructed and arranged to impart direction to the discharge from said opening.

3. A sprinkler comprising a deflector having a flat rectangular plate portion and abruptly curving side portions at each edge of the rectangular portion each side portion being symmetrically disposed in angular relation thereto and forming a circumscribing edge on said deflector arranged and constructed to impart direction to the discharge from said opening; said deflector being capable of distributing the discharge from said sprinkler over a substantially rectangular area.

4. A sprinkler adapted to effect pyramidal distribution of its discharge comprising a discharge opening; a rectangular flat plate arranged at right angles to the axis of flow through said opening whereby part of the flow is deflected at an acute angle to said axis and part is deflected approximately perpendicularly to said axis; and side portions at each edge of said rectangular portion with each side portion symmetrically disposed in angular relation to the flat plate portion and together forming a circumscribing edge therearound constructed and arranged to deflect the last said part of the flow at an abrupt angle to the original axis of flow; the combined effect of said plate and side portions being a pyramidal distribution over a substantially rectangular area.

ALBERT J. LOEPSINGER.
